[57] CLAIM

The ornamental design for a medical ultrasound transducer, as shown.

DESCRIPTION

FIG. 1 is the front right isometric view of the design of the present invention;

FIG. 2 is the bottom front right view of the design of the present invention;

FIG. 3 is the front view of the design of the present invention;

FIG. 4 is the right view of the design of the present invention;

FIG. 5 is the bottom view of the design of the present invention;

FIG. 6 is the back view of the design of the present invention;

FIG. 7 is the left view of the design of the present invention; and,

FIG. 8 is the top view of the design of the present invention.
